COMBINATION BOTTLE AND TRAY

Catherine Miller, Antioch, Ill.

Application May 6, 1955, Serial No. 35,866

Term of patent 3½ years

(Cl. D58—6)

Fig. 1

Fig. 2

Fig. 3

Fig. 4

Fig. 5

Fig. 1 is a perspective of my new design;

Fig. 2 is a bottom plan view thereof;

Fig. 3 is a side elevation thereof;

Fig. 4 is an end elevation thereof as seen from the right side of Fig. 1; and

Fig. 5 is an end elevation thereof as observed from the left side of Fig. 1.

The side of the figure not visible corresponds to that shown in Fig. 2.

What I claim is:

The ornamental design for a combination bottle and tray, substantially as shown and described.
